US0D1100567S

(12) **United States Design Patent** (10) **Patent No.:** **US D1,100,567 S**
(45) **Date of Patent:** **** Nov. 4, 2025**

(54) **AIR FRYER**

(71) Applicant: **SharkNinja Operating LLC**,
Needham, MA (US)

(72) Inventors: **Adam Garland**, Boston, MA (US);
Gregory Allan Fish, Boston, MA (US);
Alex Kibbe, Needham, MA (US);
Joshua D. Anthony, North Billerica,
MA (US); **Kevin O'Malley**, Needham,
MA (US); **Christopher Meyer-Rassow**,
London (GB)

(73) Assignee: **SharkNinja Operating LLC**,
Needham, MA (US)

(**) Term: **15 Years**

(21) Appl. No.: **29/961,223**

(22) Filed: **Sep. 4, 2024**

(51) LOC (15) Cl. **07-02**

(57) **CLAIM**

The ornamental design for an air fryer, as shown and described.

DESCRIPTION

FIG. 1 is a front perspective view of an air fryer showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a bottom perspective view thereof.

The dashed broken lines in the figures illustrate portions of the air fryer that form no part of the claimed design.
